UNITED STATES PATENT OFFICE.

RUDOLF SCHMID, JR., OF WEST ALLIS, WISCONSIN, ASSIGNEE, BY MESNE ASSIGNMENTS,
TO ALLIS-CHALMERS MANUFACTURING COMPANY, A CORPORATION OF DELAWARE.

CONNECTOR.

1,218,216.

Specification of Letters Patent.

Patented Mar. 6, 1917.

Application filed May 17, 1912. Serial No. 698,004.

To all whom it may concern:

Be it known that I, RUDOLF SCHMID, Jr., a citizen of the United States, residing at West Allis, in the county of Milwaukee 5 and State of Wisconsin, have invented certain new and useful Improvements in Connectors, of which the following is a full, clear, and exact specification.

My invention relates to connectors for 10 electrical conductors.

It is the object of my invention to provide a connector for electric conductors the parts of which can be readily assembled and taken apart, said parts being held stationary with respect to each other when 15 assembled.

The invention is illustrated on the accompanying sheet of drawings in which Figure 1 is a longitudinal sectional view 20 of my connector; and,

Fig. 2 is a longitudinal sectional view of a modification of the connector shown in Fig. 1.

The various novel features of my invention will be apparent from the description and drawing, and will be particularly set forth in the appended claims.

This connector for electric conductors includes a sleeve 10 having a reduced portion 11 which passes through an opening 12 in any suitable base or support 13. The reduced portion 11 of the sleeve 10 is provided with an annular groove 14 adjacent one side of the base for the reception of 35 a resilient member or split ring 15, which is adapted to prevent relative movement between the base 13 and sleeve 10 when the resilient member 15 is set in place. This reduced portion of the sleeve 10 forms a 40 shoulder 16 which presses against the base 13 and is held there by the resilient member 15. The sleeve 10 is also provided with a projection 17 which occupies a notch 18 in the base 13 to prevent turning of the 45 sleeve within the base. Located within the sleeve 10, as indicated in Fig. 1, are two preferably duplicate interchangeable complementary conducting members or terminals 19 and 20 which are adapted to be 50 electrically connected and held in mechanical engagement with each other by a screw 21 which passes through the overlapping portions of said terminals. This screw passes into an opening 22 in said sleeve 55 which is sufficiently large to receive the

head 23 of the screw. The head 23 of the screw normally projects into the opening 22 of the sleeve and in this way prevents relative movement between the terminals 19 and 20 and the sleeve 10. It is therefore 60 apparent that the screw 21 not only retains the terminals in electrical and mechanical engagement with each other, but also prevents relative movement between said terminals and said sleeve. 65

In the modification shown in Fig. 2 the parts are practically the same as shown in Fig. 1 with the exception that the sleeve 25 is provided with shoulder portions 26 which are normally engaged by co-operating shoulder portions 27 on the terminals 28 and 29. In this case the screw 30 holds the terminals 28 and 29 in good electrical and firm mechanical contact with each other and lies completely within the terminals. When this screw 30 is in the position shown in Fig. 2 relative movement between the terminals and sleeve is prevented by the co-operating shoulders 26 and 27 of the sleeve and terminals respectively. 75 80

By removing the screw and the resilient member in either of the connectors shown, all of the parts may be readily separated. Furthermore, when the parts are put together, all of said parts are held stationary 85 with respect to each other.

There may be various modifications of the precise form and arrangement herein shown and described, and it is my intention to cover all such modifications and arrangements which do not involve a departure from the spirit and scope of my invention 90 as set forth in the appended claims.

What I claim as new is:

1. A coupling for electrical conductors comprising a sleeve having a portion of uniform bore and an opening from the outside to the bore, interchangeable terminal elements having similar contact portions within said sleeve portion of uniform bore, and means capable of acting independently of said sleeve for connecting said terminal elements together with the contact portions in engagement, said means co-operating with said sleeve to limit the axial movement of said terminal elements relative to said sleeve. 95 100 105

2. A coupling for electrical conductors comprising a sleeve having a portion of uniform bore and an opening from the outside 110

to the bore, interchangeable terminal elements having similar contact portions within said sleeve portion of uniform bore, a screw capable of acting independently of 5 said sleeve for connecting said terminal elements with the contact portions in engagement, said screw being insertible through the opening in said sleeve, and a portion of said screw projecting radially outside the 10 bore of said sleeve whereby the connected terminal elements are restrained from axial movement relative to said sleeve through the engagement of said projecting portion of the screw with said sleeve.

15 3. A coupling for electrical conductors comprising a bored sleeve having an opening from the outside to the bore, inter-

changeable terminal elements having similar contact portions within the bore of said sleeve, instrumentalities for connecting said 20 terminal elements together with the contact portions thereof in engagement and for securing said elements against longitudinal movement relative to said sleeve while said elements are connected together, said instrumentalities including a screw element insertible to operative position through the 25 opening in said sleeve.

In testimony whereof I affix my signature, in the presence of two witnesses.
